(57) **CLAIM**

The ornamental design for a shadow ring lift assembly, as shown and described.

DESCRIPTION

FIG. 1 is a back isometric top left-side view of a shadow ring lift assembly.

FIG. 2 is a back isometric bottom left-side view thereof.

FIG. 3 is a top plan view thereof.

FIG. 4 is a bottom plan view thereof.

FIG. 5 is a back-side view thereof.

FIG. 6 is a front-side view thereof.

FIG. 7 is a left-side view thereof; and,

FIG. 8 is a right-side view thereof.

The broken lines in the drawings illustrate portions of the shadow ring lift assembly that form no part of the claimed design.

1 Claim, 6 Drawing Sheets(56)
